UNITED STATES PATENT OFFICE

FREDERICK ARTHUR FLATHER, OF LOWELL, MASSACHUSETTS

CURTAIN PACKAGE

Application filed December 12, 1929. Serial No. 413,626.

- This invention relates to a curtain package and has for its primary object to provide, in a manner as hereinafter set forth, a package consisting of a pair of curtains of the tie back type, each formed with a ruffle along one side and one end, wherein the curtains are folded in such a manner that the pair will snugly fit a container therefor without crushing or rumpling the ruffles.
- 10 A further object of the invention is to provide a package consisting of a pair of curtains of the type above mentioned folded and packed in a container in a manner to effect an advantageous display of the curtains.
- 15 when the cover is removed from the container. A further object of the invention is to provide a package consisting of a pair of curtains of the type aforesaid wherein the curtains are folded a minimum number of 20 times to enable them to be placed in a container, and wherein the curtains are oppositely disposed within the container with the body portions of the curtains occupying a central portion of the interior of the container, and with the ruffles on the curtains extending around the body portions and occupying a marginal portion of the interior 25 of the container.
- 30 A further object of the invention is to provide a package consisting of a pair of curtains arranged as aforesaid within a container which may be supported on one of its edges for the purpose of displaying the curtains if desired, and which may be shipped or otherwise handled without any likelihood of the ruffles becoming mussed or wrinkled due to disarrangement of the body portions of the curtains within the container.
- 35 40 With the foregoing and other objects in view, the invention consists of the novel construction, combination and arrangement of parts as hereinafter more particularly described, and as illustrated in the accompanying drawing wherein is shown an embodiment of my invention, but it is to be understood that the drawings and description are to be taken as illustrative and that the invention is intended to be limited only by the scope of the 45 50 claims hereunto appended.

In the accompanying drawings in which like numerals are employed to designate like parts throughout the same:

Figure 1 is a perspective view of one of the curtains forming a part of my improved 55 package.

Figure 2 is a similar view showing the curtain folded upon itself transversely.

Figure 3 is a similar view showing the curtain folded longitudinally on the dotted line 60 of Figure 2 and further showing the element for tying back the curtain when the same is applied to a window.

Figure 4 is a perspective view of the curtain after the same has again been folded 65 longitudinally on the dotted line of Figure 3.

Figure 5 is a perspective view of the curtain after the embodiment thereof shown in Figure 4 has been folded transversely on the dotted line of Figure 4. 70

Figure 6 is a perspective view of the completely folded curtain.

Figure 7 is a perspective view of a pair of curtains folded in the manner shown in Figure 6, showing the curtains in oppositely disposed, superposed relation, and in position on a rigid backing member therefor. 75

Figure 8 is a perspective view of the pair of curtains within a container with the container cover removed. 80

Figure 9 is a perspective view of the container cover.

Figure 10 is a longitudinal section through the complete package ready for shipping or storing. 85

Referring to the drawings in detail, the numeral 1 designates the body portion of a curtain rectangular in shape and of greater length than width. Extending continuously along one end edge and one side edge of the body portion 1 is a ruffle 2 which is securely fastened as by stitching to the body portion 1, and which projects, as indicated at 3 and 4, beyond the non-ruffled end edge 5 and non-ruffled side edge 6 of the body portion 1. It is contemplated that two such curtains will be folded separately so that each will assume the folded shape illustrated in Figure 6, after which one of the folded curtains will be placed upon the other with its ruffle opposite- 90 95 100

ly disposed with respect to the ruffle on the other. The superposed, folded curtains then will be secured, by means of a flexible element such as a ribbon 7, to a rigid or semi-rigid backing member 8, which is preferably formed of relatively heavy cardboard. The whole is then positioned within a container 9 which is closed by means of a cover 10 to provide a composite package as indicated in Figure 10.

In folding each of the curtains into the shape illustrated in Figure 6, it is essential that the body portion 1 be folded wholly upon itself, and that the ruffle 2 be folded wholly upon itself. In carrying out the foregoing aim, I prefer to fold the body portion 1 transversely to provide a transverse folded edge 11, with the non-ruffled end edge 5 abutting the anchor portion 12 of the ruffle 2 at the opposite end of the body portion 1. When the body portion 1 is thus folded, the portion of the ruffle 2 extending along the side edge of the body portion is folded upon itself coincidentally, and the projecting end edge 3 assumes a position substantially bisecting the angle between the portions of the ruffle extending along a side and end respectively of the body portion 1.

The next step in folding the curtain into the shape illustrated in Figure 6 consists of folding the transversely folded body portion longitudinally to provide a folded longitudinal edge 13, with the non-ruffled side edge 6 lying adjacent the anchor portion 12 of the ruffle at the opposite side edge of the body portion 1. Coincidentally with the folding of the body portion to provide the folded edge 13, the portion of the ruffle extending along an end of the body portion is folded upon itself and the projecting end edge 4 of the ruffle assumes a position substantially bisecting the angle between the portions of the ruffle extending along a side and end respectively of the body portion 1. In this position, the end edges 3 and 4 of the ruffle are disposed substantially in opposed, abutting relation.

Before making the next fold in the curtain, I place upon the body portion a ruffled tie back element 14 such as is ordinarily used to gather a lower portion of a curtain of this type when the same is applied to a window. The element 14 is positioned on the folded body portion to extend longitudinally thereof, and preferably is folded transversely, substantially midway between its ends. The element 14 is positioned off-center with respect to the width of the folded body portion so as to be enveloped between the next created folds of the body portion without wrinkling or otherwise disturbing the position of the element 14. The body portion then is folded again longitudinally thereof to bring the folded edge 13 substantially flush with the non-ruffled edge 6, which forms a

new folded side edge 15 and causes the curtain to assume the elongated shape illustrated in Figure 4. The curtain is then folded transversely, substantially on a line indicated by the dotted line in Figure 4, thereby positioning an end portion 16 of the folded curtain upon the central portion 17 thereof, and forming a folded end edge 18. The opposite end portion 19 is then folded upon the end portion 16 with the anchor portion 12 of the ruffle substantially flush with the folded end edge 18, whereby the body portion of the curtain assumes a rectangular shape as indicated in Figure 6, having a non-ruffled end edge 20 and a non-ruffled side edge 15.

The other curtain of the pair is now folded in the same manner as above described into the shape illustrated in Figure 6 and the folded body portion thereof is positioned on the folded body portion of the first curtain of the pair with the non-ruffled end and side edges corresponding to the edges 20 and 15 respectively, oppositely disposed with respect to the edges 20 and 15. In this manner the folded body portions of the pair of curtains are disposed in superposed relation with the ruffles of the respective curtains lying outside the vertical plane of the body portions at opposite sides and ends of the latter whereby the ruffles are extended entirely around the body portions at the edges of the latter. The superposed curtains are then secured to the backing member 8 by means of the ribbon 7 and positioned within the container 9, after which the cover 10 may be secured in position in any suitable manner.

It is to be noted that the backing member 8 fits snugly within the container 9 whereby any edgewise movement of the member 8 is prevented regardless of the position in which the container may be placed. It is to be noted further that the body portions of the curtains are disposed with their edges in equi-spaced relation to the side and end walls of the container and fit snugly between the backing member 8 and cover 10 when the latter is drawn into closure position. Thus a space is provided within the container which extends entirely around the edges of the body portions, which space is substantially filled by the ruffles 2 when the latter are in a fluffed condition. With the curtains packed in this manner, any amount of rough handling of the container will have no disarranging effect on the ruffles, and, regardless of the length of time that the curtains may remain in the container, an attractive display of the curtains meets the eye immediately upon the removal of the cover.

It is thought that the many advantages of a package in accordance with this invention will be readily apparent, and, although the application of the invention to a pair of curtains of a certain type and of a standard size has been specifically described, it is to be

understood that the relative dimensions of the various parts may be varied as may become necessary to apply the invention to curtains of odd size or shape, so long as the relative positions of the parts as hereinbefore set forth is maintained.

It is to be understood further that the number of folds of the body portion of a curtain may be increased or diminished as the size or shape of the curtain may require so long as the body portion is folded upon itself, and the ruffle portion is folded upon itself. It is to be understood further that the depth of the container may be increased to permit the packing therein of any number of curtains desired.

What I claim is:—

1. A package formed of a pair of curtains, each including a body portion having a ruffle extending across one side and one end thereof, said ruffles having anchor portions fixedly secured to said body portions at the edges of the latter, each of said body portions being folded upon itself transversely and longitudinally with the non-ruffled side and end edges thereof abutting the anchor portion of the ruffle at the side and end respectively of the body portion, said ruffle being folded transversely coincidentally with the folding of the body portion, the folding of the body portion providing a folded side edge and a folded end edge for the folded body portion, said body portion being further folded longitudinally with said folded side edge substantially flush with said non-ruffled side edge, said body portion being further folded transversely with said folded end edge spaced from said ruffle at the end of the body portion, said last named fold providing a second folded end edge for the body portion and disposing an end portion of the folded body portion on a central portion thereof, the other end portion being folded to seat upon the first named end portion with the anchor portion of the ruffle secured thereto substantially flush with said second folded end edge of the body portion, said folded body portions being oppositely disposed in superposed relation.

2. A package formed of a pair of curtains, each including a body portion having a ruffle secured to and extending along a side edge and an end edge thereof, each of said body portions being folded upon itself transversely and longitudinally whereby the ruffle is extended beyond the non-ruffled side and end edges of the body portions, said ruffle being folded transversely coincidentally with the folding of the body portion, the folding of the body portion providing a folded side edge and a folded end edge for the body portion, said body portion being further folded longitudinally with said folded side edge substantially flush with said non-ruffled side edge, said folded body portion being further

folded transversely with said folded end edge spaced from said ruffle at the end of the body portion, said last named fold disposing an end portion of the folded body portion on a central portion thereof, the other end portion of the folded body portion being folded to seat on the first named end portion with the ruffle secured to the former projecting beyond the latter, said folded body portions being disposed in superposed relation with the ruffles secured thereto projecting therefrom in opposite directions.

3. A package formed of a pair of curtains, each including a body portion having a ruffle secured to and extending along a side edge and an end edge thereof, each of said body portions being folded upon itself transversely and longitudinally whereby the ruffle is extended beyond the non-ruffled side and end edges of the body portion, said ruffle being folded transversely coincidentally with the folding of the body portion, the folding of the body portion providing a folded side edge and a folded end edge for the body portion, said body portion being further folded longitudinally with said folded side edge substantially flush with said non-ruffled side edge, said folded body portion being further folded transversely with said folded end edge spaced from said ruffle at the end of the body portion, said last named fold disposing an end portion of the folded body portion on a central portion thereof, the other end portion of the folded body portion being folded to seat on the first named end portion with the ruffle secured to the former projecting beyond the latter, said folded body portions being disposed in superposed relation with the ruffles secured thereto projecting therefrom in opposite directions, and a container having said curtains disposed therein, said superposed body portions being disposed centrally of the container in spaced relation to the side and end walls thereof to provide a space extending around the edges of the body portions, said projecting ruffles extending into said space and substantially filling the same when in a fluffed condition.

4. A package formed of a pair of curtains, each including a body portion having a ruffle secured to and extending along a side edge and an end edge thereof, each of said body portions being folded upon itself transversely and longitudinally whereby the ruffle is extended beyond the non-ruffled side and end edges of the body portion, said ruffle being folded transversely coincidentally with the folding of the body portion, the folding of the body portion providing a folded side edge and a folded end edge for the body portion, said body portion being further folded longitudinally with said folded side edge substantially flush with said non-ruffled side edge, said folded body portion being further folded transversely with said folded

- end edge spaced from said ruffle at the end of the body portion, said last named fold disposing an end portion of the folded body portion on a central portion thereof, the other end portion of the folded body portion being folded to seat on the first named end portion with the ruffle secured to the former projecting beyond the latter, said folded body portions being disposed in superposed relation with the ruffles secured thereto projecting therefrom in opposite directions, a rigid backing member upon which the superposed body portions are secured with the projecting edges of the ruffles substantially flush with the edges of the backing member, and a container having said backing member and curtains disposed therein, said backing member snugly engaging the side and end walls of the container.
5. A package formed of a pair of curtains, each including a body portion having a ruffle secured to and extending along a side edge and an end edge thereof, each of said body portions being folded upon itself transversely and longitudinally whereby the ruffle is extended beyond the non-ruffled side and end edges of the body portion, said ruffle being folded transversely coincidentally with the folding of the body portion, the folding of the body portion providing a folded side edge and a folded end edge for the body portion, said body portion being further folded longitudinally with said folded side edge substantially flush with said non-ruffled side edge, said folded body portion being further folded transversely with said folded end edge spaced from said ruffle at the end of the body portion, said last named fold disposing an end portion of the folded body portion on a central portion thereof, the other end portion of the folded body portion being folded to seat on the first named end portion with the ruffle secured to the former projecting beyond the latter, said folded body portions being disposed in superposed relation with the ruffles secured thereto projecting therefrom in opposite directions, a rigid backing member upon which the superposed body portions are secured with the projecting edges of the ruffles substantially flush with the edges of the backing member, and a container having said backing member and curtains disposed therein, said backing member snugly engaging the side and end walls of the container, said container having a cover seating on the uppermost of said superposed body portions.
6. A package formed of a pair of curtains, each including a body portion having a ruffle secured to and extending along a side edge and an end edge thereof, each of said body portions being folded longitudinally and transversely, each of said ruffles being folded transversely and projecting from a side and an end of the body portion to which it is se-
- cured, said body portions being disposed in superposed relation with the ruffles secured thereto projecting therefrom in opposite directions.
7. A package formed of a pair of curtains, each including a body portion having a ruffle secured to and extending along a side edge and an end edge thereof, each of said body portions being folded longitudinally and transversely, each of said ruffles being folded transversely and projecting from a side and an end of the body portion to which it is secured, said body portions, being disposed in superposed relation with the ruffles secured thereto projecting therefrom in opposite directions, and a container having said superposed body portions disposed therein in spaced relation to the walls thereof, said ruffles projecting in opposite directions from the body portions and substantially filling the space between the body portions and the walls of the container.
- In testimony whereof, I affix my signature hereto.
- FREDERICK ARTHUR FLATHER.
